UNITED STATES PATENT OFFICE.

FREDERICK S. McCULLOUGH, OF CLEVELAND, OHIO, ASSIGNOR TO GLENN L. MARTIN,
OF CLEVELAND, OHIO.

RADIO APPARATUS.

Application filed January 9, 1920. Serial No. 350,362.

My invention relates to radio apparatus, and particularly to that part of the apparatus which is designed to detect, amplify or transmit radio oscillations. The general object of the invention is to increase the efficiency of and simplify such apparatus.

My invention consists of means herein-after fully described and particularly set forth in the claims.

10 This application is a continuation in part of my pending application Serial No. 128,375 filed October 30, 1916, now issued as Patent No. 1,403,700 of January 17, 1922, in so far as relates to that part of the subject 15 matter herein which is common to both applications.

The annexed drawings and the following description set forth in detail certain means embodying my invention, the disclosed 20 means, however, constituting but one of various forms in which the principle of the invention may be used.

In said annexed drawings:

Fig. 1 is an explanatory diagram designed 25 to illustrate the theory underlying the principle and the operation of my invention;

Fig. 2 represents a diagram of a simple form of my radio apparatus;

Figs. 3, 4 and 5 represent modifications of 30 apparatus employing the principle of my invention.

Referring first to Fig. 1: 44 is a non-oxidizable heating filament which may, as will hereinafter appear, be kept at a certain predetermined temperature. In series 35 with this filament is a battery 10 and rheostat 3 connected by wires 41 and 57, the temperature being adjusted by rheostat 3. Surrounding this filament 44 is an element 40' consisting of semi-dielectric material, such 40 as glass. Surrounding this element 40' and in physical contact therewith is a control coil 45, which is connected to the antennæ 8 by the wire 9. The opposite end of this coil 45 is left free. Surrounding the coil 45 is a 45 second coil 55, which is in series with a second battery 56 and a rheostat 58. This latter coil surrounds and is in physical contact with a second tube 40, also consisting of a 50 semi-dielectric material such as glass, and out of physical contact with the control coil. This coil 55 is connected with the positive pole of a source 56 of power, herein shown to be a battery, the other pole being con-

nected by means of wire 57 with one end of 55 filament 44, as shown.

When filament 44 is heated so that it will glow, it emits electrons. The coil 55, being connected in series with the battery 56, is also heated and this heat is transmitted to 60 the glass tubes 40 and 40' which it surrounds, thus placing them in a state of ionization. The glass thereby becomes conductive, rendering these glass tubes electrolytic and the electrons pass therethrough as a result of such heating. This being the case, and the coil 55 being connected positively with the battery 56, the electrons will pass through the glass, which is an electrolyte, to coil 55. As a result, current will flow from 65 coil 55 to filament 44 in the opposite direction from the flow of electrons. That the current does so flow may be shown by means of the ammeter A or other indicating device 70 which may be introduced into the circuit as 75 shown in Fig. 1.

When electromagnetic waves impinge on the antennæ 8, passing along the wire 9 to control electrode 45, they will alter the flow 80 of current from coil 55 to filament 44, and this alteration will be indicated on ammeter A.

This arrangement of parts, it will also be noted, makes of the filament 44 a cathode, and of the coil 55 an anode, and the interposed coil 45 a control member. It must also be understood that the coil 55 is also a local control member, for by raising or lowering the current flow in said coil, electrolytic action, i. e., the conductivity to electron flow will be increased or decreased accordingly, and any fluctuations which may result from said local control may then be noted on ammeter A, due to the consequent variation in the current in the filament circuit. 95

In Fig. 2 I have illustrated a modification of the above described apparatus also embodying the principles of my invention. In this apparatus, an enclosed and evacuated vessel 40 is provided, which consists of the semi-dielectric material such as glass or the like, through which passes the filament 44. This filament in the particular arrangement shown is in series in a circuit including the 100 source of power 10, together with a variable inductance 16 and variable condensers 70—75 and 80—85, by means of which the cur-

rent passing through the filament due to the charge effect on the condensers may be regulated and the latter heated to the predetermined incandescence. By enclosing the filament in an evacuated tube, I am enabled to increase this incandescence to a greater degree than if this filament were not enclosed. In the interior of the tube and adjacent to and interposed between the tube's walls and the filament, is the control element 45 herein shown to consist of a flat plate. This plate is connected in series with the positive pole of the source of power 47, herein shown to be a battery, the negative pole of this battery being connected with one end of the filament by means of the wire 11.

Surrounding the exterior of the glass tube 40 and preferably in physical contact therewith is the heating coil 55, which is connected in series with a source of power 56 herein shown to be a generator of high or radio-frequency currents. This high frequency generator produces alternating currents of frequencies corresponding to or approaching the frequency of the circuit including generator 10, so that the coil 55 will produce in tube 40 an oscillating field of a frequency substantially coincident with the frequency of the received impulses impressed or induced on capacities 75 and 85. The effect of this oscillating field is to heat the cathode and tube and ionize the attenuated gas within the tube and to attract and repel the electron flow from the heated cathode toward 35 and from the walls of the vessel in a variable manner, in a direct relation to the oscillating frequency of the received impulses from generator 10. In this circuit, also, is the rheostat 58, by means of which the passage 40 of current through the coil 55 may be regulated.

When current is passed through the filament 44 and the latter raised to incandescence, electrons are emitted and impinge 45 the interior surface of the tube or vessel 40. Current is simultaneously passed through the heating coil 55 so as to raise the same to the required temperature. This heating coil heats the latter and converts it to a state of 50 ionization, thereby rendering it conductive, thus setting up an electrolytic action, the glass acting as an electrolyte. Current is therefore thus permitted to pass from the anode coil 55 to the cathode filament 44.

55 The element 45 within the tube is the electron control; that is to say, it modifies the flow of electrons between the filament 44 and the coil 55. This control may be effected by varying the potential of the battery 47, as shown, or by any other suitable means which will vary the conditions of the circuit containing the element 45. Any interaction 60 between the circuit containing the anode 55 and the filament 44 and the circuit containing 65 the control member would necessarily af-

fect the conditions of the control due to the conductive and inductive interconnection of said circuit. Such inter-action is shown, for instance, where the coil 55 is wound about the tube within which is a control member 70 45. As the currents in coil 55 vary, they will induce a variation in the condition of control member 45. This variation in 45 will in turn vary the electron flow between the filament and the anode 55. 75

Fig. 3 represents a further modification, wherein 40 is an evacuated glass tube, and 40' is a surrounding evacuated glass tube, 55 being the ionizing means and the anode, surrounding tube 40 and in physical contact therewith. The tube 40' is provided to prevent the ionizing means from oxidizing. To regulate the current flow, rheostat 58 is placed in series. This coil 55 is connected to the positive pole of source of power 56. 80 Within this tube 40 is the incandescent filament 44. The source of power for making this filament incandescent is shown to be a generator 10 for exciting the oscillator. The variable condensers 70—75 and 80—85 regulate the current. Interposed between this filament and the coil 55 is the control member 45. This control member leads out of the tube 40 and is connected by a wire 12 to the inductance 20, and the center of this inductance is connected to the filament. The opposite end of this inductance 20 is connected through the ammeter A to the negative side of the source of power 56. The tuning condensers 21 and 22 show means for tuning these circuits. The condenser 23 is provided to facilitate the stopping of audio-frequency noises from the power source 56. 86 and 87 are mica shields to prevent the stems 88 and 89 from becoming ionized which is very important in an electrolyte device. 90

Fig. 4 represents another modification of the device wherein 40 is an evacuated tube, 55 the ionizing means or the anode, and 45 110 a helical coil having a definite inductance and capacity value. 40' is an evacuated outer tube. 44 is the filament, and 10 a source of power for making the filament incandescent, 3 being a rheostat for regulating the current flow. The condensers 24 and 25 have been included for purposes of tuning and also the variable inductance 20 introduced. The power for the anode circuit is derived from source 56 passing through impedances 26 and 27 and across these the audio-frequency smoothing-out condenser 23 is placed. By this structure, anode 55 becomes an inductance and the control 45 also an inductance. Condensers 24 and 25 are means for varying the frequency of the oscillations in the respective circuits containing said inductances. By the action of the inductances 55 and 45 I am able to make this device self-exciting. 115 120 125

Fig. 5 illustrates a purely self-exciting oscillation generator wherein 55 is a tuned ionizing means and anode coiled about the tube 40. Its power is taken from the source 56, made adjustable by rheostat 58, the ionizing anode inductance 55 being tuned by condenser 25. 45 is a tuned controlling inductance member within this tube connected to the negative side of the filament 44. The filament 44 is made incandescent by the local battery 10 and regulated by the rheostat 3. The action which takes place is as follows: When filament 44 becomes incandescent, it will, as already described, emit free electrons which impinge upon the inner wall of the semi-dielectric tube 40 and would remain there if this glass-like wall were not placed in a state of ionization. The anode 55 is connected to the positive pole of the source of power 56, to the inductance 29. This inductance 29 is so constructed as to be variable and to have a portion slide over the tube 40 and to bring it to inductive relation with coil 45. Across the inductance 29 is placed a condenser 30 for tuning purposes. The opposite end of this inductance is connected to the filament 44 by wire 31. To facilitate further tuning, condenser 24 is placed in series with the coil 45 and the negative side of source of power 56. By so doing, I obtain a powerful oscillator. To propagate these oscillations, I attach to the coil 29 an antenna 8 and ground connection 13 which runs to the filament passing through ammeter A, thus placing a load on the device so that it will radiate electromagnetic waves.

The principles of my invention, as will be understood by those skilled in the art, may be used in a detector, amplifier, oscillator, or oscillation generator.

In every case, with the exception of Fig. 1, the external coil is in circuit with a high frequency generator, as in Fig. 2, or in a regenerative circuit wherever radio frequency oscillations are impressed on the coil, as in the other figures. These radio frequency oscillations in the coil have an ionizing action on the residual gases in the tube, rendering the gas conductive and at the same time this state of ionization of the gas, due to the friction of the ions and molecules, will raise the temperature of the glass envelope, ionizing it; that is, rendering it conductive, while also heating any metal parts within the tube. Where the circuit is organized as in Fig. 2, the inductive action of the oscillating field within the tube produced by coil 55 is the principal means for heating cathode 44, as the charge effect on capacities 70—75 and 80—85 would generally be insufficient to effect this, as is the case where the sending and receiving stations are remotely located. In other words, the heating of the filament by the charge effect on

the capacities 70—75 and 80—85 is incidental and normally negligible.

What I claim is:

1. In a radio apparatus, the combination of a filament, a glass-like wall surrounding said filament, means for heating the filament; means for heating the wall; said filament and heating means constituting electrodes of an electrical circuit.
2. In a radio apparatus, the combination of a sealed globe; a filament within said globe; means for heating the filament; means for heating the globe; and an electron control adjacent said filament within said globe; said filament and heating means constituting electrodes of an electrical circuit.
3. In a radio apparatus, the combination of an evacuated globe; a filament within the globe; means for heating the filament; and means for heating the globe; said filament and heating means constituting electrodes of an electrical circuit.
4. An electron valve comprising a sealed globe having an end portion through which conductor elements pass; a filament within said globe forming an electrode of an electric circuit; a conductor element forming a second electrode; and a mica shield interposed between said filament and the end portion of said globe.
5. In radio apparatus, the combination of a partially evacuated globe; a filament within the globe; means for heating the filament; and means outside of the globe for heating said filament; said filament and said globe heating means constituting electrodes of an electric circuit.
6. An electron valve comprising a sealed globe having conductor elements entering opposite ends thereof; a filament within said globe connected to said conductor elements; an anode conductor outside said globe; and mica shields interposed between said filament and end portions of said globe.
7. The combination with a thermionic tube having an electron emitting cathode therein and having an attenuated gaseous content, an energy receiving capacity in circuit with the cathode, a second electrode within the vessel, a local battery having one terminal connected with said electrode and one terminal in circuit with said cathode, a coil surrounding the tube, and a local generator for impressing radio frequency currents on said coil, whereby said coil may maintain an ionizing field in said tube oscillating at radio frequency.
8. The combination with a partially evacuated vessel having an electron emitting cathode and in which there is a gas content, of a coil associated with the vessel, a local source of radio frequency oscillations in circuit with the coil, said coil and source constituting means for producing an oscillating field within the tube and for heating the

cathode for effecting electron emission therefrom.

9. The combination with a thermionic tube having an emitting cathode therein and having an attenuated gaseous content, of means for ionizing said gaseous content and heating the cathode to sustain electron emission therefrom comprising an external coil and a generator of radio frequency oscillations in circuit with the coil.
10. The combination with an electron tube having a cathode therein and having an attenuated gaseous content, of a coil surrounding the cathode in inductive relation thereto, and a local generator of high frequency currents in circuit with the coil, said coil and generator constituting means for
- 15

maintaining an oscillating field in the tube to effect ionization of gases therein and effect heating of the cathode to sustain electron emission therefrom.

11. The method of heating a cathode to effect electron emission therefrom in an evacuated vessel in which there is a gaseous residuum by means of a surrounding coil which consists in passing radio frequency currents through said coil and thereby produce an oscillating field within said vessel having sufficient energy to heat the cathode whereupon electron emission is effected.

Signed by me, this 29th day of December, 1919.

FREDERICK S. McCULLOUGH.
